UNITED STATES PATENT OFFICE.

FRANK A. PETERS, OF CHICAGO, ILLINOIS.

CURTAIN-SUPPORT.

1,327,961.

Specification of Letters Patent. Patented Jan. 13, 1920.

Application filed May 12, 1919. Serial No. 296,421.

To all whom it may concern:

Be it known that I, FRANK A. PETERS, a citizen of the United States, and a resident of the city of Chicago, in the county of 5 Cook and State of Illinois, have invented certain new and useful Improvements in Curtain-Supports; and I do hereby declare that the following is a full, clear, and exact description of the same, reference being had 10 to the accompanying drawings, and to the numerals of reference marked thereon, which form a part of this specification.

This invention relates to curtain supports and although not limited to such use is particularly adapted for use with window curtains.

Hitherto curtains have been supported from rods resting on brackets secured to each side of the window frame so that to 20 replace a dirty curtain by a clean one it is usually necessary to use a step ladder.

One of the principal objects of the invention, therefore, is to provide convenient means for lowering the curtain to such a 25 height that it may be removed and replaced without recourse to step ladders or similar devices.

A further object of the invention is to provide means for swinging the curtain as 30 a whole toward or away from the window.

Other and further important objects of this invention will be apparent from the disclosures in the specification and drawings.

The invention (in a preferred form) is 35 illustrated in the drawings and hereinafter more fully described.

On the drawings:

Figure 1 is a front elevation of a window equipped with a device embodying the in- 40 vention.

Fig. 2 is a plan view of the device with parts broken away and other parts in section.

Fig. 3 is a front elevation of the device 45 with parts broken away.

Fig. 4 is a view taken on the line 4—4 of Fig. 2 with parts removed.

Fig. 5 is a view similar to Fig. 1 showing the device in lowered position.

50 Fig. 6, is a section on the line 6—6 of Fig. 2.

Fig. 7, is a view similar to Fig. 6 with parts removed.

Fig. 8 is a section on the line 8—8 of 55 Fig. 3.

Fig. 9 is a section on the line 9—9 of Fig. 2.

Fig. 10 is a section on the line 10—10 of Fig. 9.

Fig. 11 is a section on the line 11—11 of 60 Fig. 3.

Fig. 12 is a section on the line 12—12 of Fig. 6.

As shown on the drawings:

The device consists of a curtain support 65 adapted to extend horizontally across the top of a window frame 1, and to be lowered and (or) swung outward away from the window if desired.

The curtain support comprises a tube 2, 70 into the ends of which rods 3 and 4 are telescopically mounted. One of these rods, as 3, is bent toward the window and then downwardly to space the curtain away from the window and also to connect the support 75 to a rod 12, for raising and lowering it. The other rod 4, is bent toward the window for releasable engagement with a catch device 5, when the support is in its elevated position.

The downwardly projecting extension 12 of the rod 3, passes through a releasable locking device 6, by means of which the rod 12, and thereby the curtain may be held in any desired vertical position. The upper 85 end of the rod 12, is supported by an arm 7, slidably mounted at one end on a rod 8, secured at its ends by brackets 9 and 10 to the window frame. In the rod 8, a key-way 90 is formed with which a key 11, on the arm 7, engages. By this means rotation of the arm 7, relatively to the rod 8, is prevented.

On the other hand, the rods 3 and 12, are free to rotate in the opposite end of the arm 7, to enable the support and the curtain carried thereby to be swung toward and away 95 from the window. To prevent longitudinal movement of the rods 3 and 12, relatively to the arm 7, the upper end of the rod 12, is flanged at 13, for contact with the lower side of the arm 7, while the lower end of the rod 3, is similarly flanged at 14, for contact with the upper side of the arm 7.

A sleeve 15, formed integrally with the rod 12, provides the necessary bearing surface for the rod 12, 100 in its rotation in the arm 7. The two rods 3 and 12 are conveniently connected screwing the threaded end 16, of the rod 3 into the sleeve 15. Preferably the sleeve 15 is

slightly longer than the thickness of the arm 105

110

Fig. 8 is a section on the line 8—8 of Fig. 3.

7, so that the rods 3 and 12, may be screwed tightly together without preventing free rotation of the rods relatively to the arm 7.

The rod 4, is releasably secured to the 5 window frame when the support is in its elevated position by a catch device 5, shown more particularly in Figs. 2, 4, 6 and 7. This catch is conveniently constructed of a rectangular metal case 17, with an outwardly flaring opening 18, to aid in guiding the end of the rod 4, into its interior.

Within and suitably secured to the case 17, is a second rectangular case 19, outwardly flanged at 20, along its vertical edges to enable the device as a whole to be attached to the window frame. The sides of the inner case 19, are cutaway at their forward edges to provide space for the ends of rollers 21 and 22, arranged within the outer case 17. 15 Projections 23, are provided on such edges to prevent the upper roller 22, falling into contact with the lower roller 21, and thus leave a slit between the rollers as shown in Fig. 4. The end of the rod 4, is beveled 20 top and bottom to provide a pointed end which may be pushed between the rollers 21 and 22 to bring a recess 24, in the underside of the rod 4, into engagement with the lower roller 21. A spring 25 is provided for depressing the roller 22 and thereby releasably holding the rod 4, in engagement with the lower roller 21.

The support is swung toward and away from the window by means of a handle 26, 35 pivotally secured at 27, to the lower end of the rod 12. It is evident that means must be provided for insuring that, when the support has been moved to its elevated position and swung toward the window by the handle 40 26, the end of the rod 4 registers with the slot between the rollers 21 and 22, of the catch device 5. Consequently as rods 3 and 4, are telescopically mounted in the ends of the tube 2, means are provided for preventing 45 rotation of these rods relatively to the tube. For this purpose each of the rods is fluted or provided with a key-way 33, into which a tongue 34, on the end of the tube 2, is arranged to project as shown more particularly in Fig. 12.

The vertical position of the support is determined by the catch device 6, which comprises a casing 28, within which are arranged a pair of apertured plates 29, 55 through which the rod 12, is passed. A spring 32 on the rod 12, between these two plates presses them apart and since their rear edges are engaged by lugs 30 on the casing 28, the front portions of the plates are moved apart. This twisting movement of the plates relatively to the rod 12 causes the edges of the apertures in the plates to bind 60 against the rod and thereby prevent any longitudinal movement of the latter. For releasing these plates a press button 30', is

provided and secured at its inner end to a U-shaped member 31, engaging the outer edges of the plates 29. The arms of this member 31 are inclined so that when the button 30' is pressed inward these inclined 70 arms force the plates 29 together against the action of the spring 32 and release the rod 12.

The operation is as follows:

Assuming the curtain and its support are 75 in the position shown in Fig. 1 the first step in removing the curtain to replace it by a clean one is to grasp the handle 26. The push button 30' is then depressed to release the rod 12. After that has been accomplished 80 the handle 26 is moved to the right thereby disengaging the end of the rod 4, from the catch 5. The curtain and its support may then be lowered and swung outwardly into the position shown in full lines 85 in Fig. 5, holding the button 30', depressed while so doing. The rod 4, may then be readily slid out of the end of the tube 2, the curtain replaced by a clean one and the rod 4, reinserted the correct distance in the 90 tube 2. The push-button 30' is then pressed and the rod 12, with the other parts, lifted by the handle 26, to their upper limit of movement. The latter is then swung to the right to bring the rod 4 into engagement 95 with the catch 5, after which the push-button 30' is released.

If at any time an unobstructed view out of the window is desired or if the clear passage of air through the whole window is 100 desired, particularly in the case of casement windows, the support may be swung to one side by depressing the button 30', and moving the handle 26, to the right.

I am aware that numerous details of construction may be varied through a wide range without departing from the principles of my invention and I therefore do not pur- 105 pose limiting the patent granted further than necessitated by the prior art.

I claim as my invention:

1. A device of the kind described comprising a vertical longitudinally movable member, a horizontal member secured to the upper end thereof and adapted to support 115 a curtain, fixed and vertically movable guiding means for said member, and means for holding the vertical member in adjusted position longitudinally.

2. A device of the kind described comprising a frame, a vertical member secured thereto adapted to reciprocate longitudinally and also rotate relatively to the frame, a horizontal member carried by the vertical member and adapted to support a curtain, 120 and means for releasably securing the horizontal member to the frame.

3. A device of the kind described comprising a frame, a horizontal member piv- 125 otally connected at one end to one side of 130

- the frame adapted to support a curtain, and a catch for releasably securing the other end of said member to the other side of the frame.
- 5 4. A device of the kind described comprising a movable vertical member, a horizontal member carried thereby and adapted to support a curtain, and means for guiding the upper end of the vertical member irrespective of its vertical position.
- 10 5. A device of the kind described comprising a frame, a horizontal member connected thereto adapted to support a curtain, means for raising and lowering said member relatively to the frame without changing the horizontal relation of such member, and means for releasably securing the horizontal member to the frame when it is in raised position.
- 15 6. A device of the kind described comprising a movable vertical member, a horizontal member secured to the upper end thereof and adapted to support a curtain, and means for guiding the upper end of the vertical member in any vertical position.
- 20 7. A device of the kind described comprising a frame, a vertical member, a horizontal member carried thereby and adapted to support a curtain, means for moving the vertical member longitudinally relatively to the frame, guiding means secured to the frame for supporting such member during such movement, and means for releasably clamping the vertical member in position. 30
- 25 8. A device of the kind described comprising a movable vertical member, a horizontal member adapted to support a curtain secured thereto, a fixed vertical guiding member, and connecting means slidably but not rotatably engaging the guiding member and rotatably engaging the movable vertical member but not slidable thereon. 35

In testimony whereof I have hereunto subscribed my name in the presence of two subscribing witnesses.
